UNITED STATES PATENT OFFICE

97,628

DESIGN FOR A TEXTILE FABRIC

Arthur White, Uxbridge, Mass., assignor to Uxbridge Worsted Company, Inc., Uxbridge, Mass., a corporation of Massachusetts

Application August 6, 1935, Serial No. 57,975

Term of patent 3½ years

To all whom it may concern:

Be it known that I, Arthur White, a citizen of the United States, residing at Uxbridge, in the county of Worcester, State of Massachusetts, have invented a new, original, and ornamental Design for Textile Fabrics, of which the following is a specification, reference being had to the accompanying drawing, forming part thereof.

In the accompanying drawing:—

Figure 1 is a face view of a textile fabric, showing my new design; and

Figure 2 is a cross section of said fabric, taken on the line 2—2 in Figure 1.

The design unit, as shown in the accompanying drawing, is outlined by the dot-and-dash

line, and the design is repeated over the surface of the fabric in the directions of the length and width of the fabric, it presenting relatively depressed areas of plain woven appearance and relatively raised areas presenting filling and warp ribs having a curved appearance, the depressed and raised areas extending in parallel rows across the fabric in a diagonal direction of approximately 45 degrees. The fabric is woven and is in a single color.

I claim:

The ornamental design for a textile fabric, as shown and described.

ARTHUR WHITE.
